UNITED STATES PATENT OFFICE.

FRANZ LAWACZECK, OF POCKING, GERMANY, ASSIGNOR TO THE WORTHINGTON PUMP AND MACHINERY CORPORATION, OF NEW YORK, N. Y., A CORPORATION OF VIRGINIA.

TURBINE-DRIVEN ROTARY PUMP.

Application filed August 29, 1921, Serial No. 496,548, and in Germany June 3, 1915. Renewed December 18, 1925.

Pumps driven by water turbines, such as the bilge pumps frequently used on ships, are the more economical for the same output, the higher the pressure used for driving their turbines is in comparison with the head of the pump, because the higher the said pressure is the smaller the quantity of water that has to be admitted into the turbine will be in comparison with the quantity of water taken in and raised by the pump. It is known that the water admitted into the turbine, after expending its force, also has to be raised by the pump. On account of the high pressure of the impelling water of the turbine, which was very liable to result in exceedingly great friction between the rotor and the water, the usual practice has been to construct the turbine for a number of pressure stages, especially because the most favorable speed of revolution of a single-stage turbine adapted for such high pressures would be much too high for a directly coupled pump, particularly if its head were small. But a multi-stage arrangement, on account of the partitions between the various divisions and their close joints at the shaft, makes the construction of the entire machine unit so complicated and its taking apart and examination so difficult that a unit of this kind could not be used in places that are difficult of access.

In accordance with one feature of the invention these drawbacks are removed by constructing the high-pressure turbine in the form of a single-stage machine mounted on a common shaft with the pump rotor, which latter is provided with spiral channels so that, even at high speeds of revolution, it will still raise the desired comparatively large quantities of water without producing undesirable high pressures. This arrangement provides the important advantage whereby, after removing the cover of the casing, the entire rotor of the machine unit can easily be taken out and examined.

As these pumps are frequently installed in low rooms which are difficult of access it is necessary to provide them with means for

balancing the axial thrust occurring in them which is reliable in operation and requires no looking after. The automatic arrangements ordinarily employed for balancing axial thrust have hitherto been imperfect on account of the small surfaces and particularly the small pressures available for this purpose. These shortcomings are entirely overcome by the present invention by its enabling the pressure used for driving the turbine, i. e. water under high pressure, to be employed for the purpose of balancing the said axial pressures. For the purpose of controlling even the greatest axial thrust that is liable to occur it is possible in addition to employing the admission pressure acting on the one side of the turbine or pump, to make the water pressure in the gap at the other side operate a second automatic arrangement for balancing axial thrust.

Another feature of the invention consists in making pumps of the said kind that are difficult of access self-starting by conducting the water discharged from the turbine straight into the suction space of the centrifugal pump so as to fill this space with water and cause the pump to start delivering in a very short time.

By this arrangement and particularly if the machine unit is made self-lubricating by causing the impelling water of the turbine to pass through its bearings, the combined pump and its power machine are united into a unit which is so simple and easy to convey that it is suitable for a great variety of uses that were outside of the province of centrifugal pumps, which, up to present, have always been stationary and not self-starting. For example the new machine unit can be conveniently connected to hose used for extinguishing fires in the same way as a nozzle is joined to a hydrant by means of a hose. The novel, simple machine may also be used on ships as a main or auxiliary bilge pump, or in mines as a mud pump in which latter case water under pressure is taken from the main mine pump and the impelling water discharged from the turbine is conducted into the blades of the pump rotor in order to

prevent them from being choked up by the mud.

A constructional form of the invention is illustrated in the drawing in which—

5 Fig. 1 is a vertical section through the centre of the machine unit,

Fig. 2 shows a view of the pump rotor with its spiral channels and

Fig. 3 is a view of the closed machine.

10 The machine unit shown in the drawing is constructed in the form of a bilge pump with a vertical shaft 10. The turbine 11 in the upper part of the casing receives impelling water under a high pressure through the in-

15 let conduit 12 which leads into the annular chamber 13. The impelling water, before entering the rotor 11, passes through guide channels 14. The water leaving, or dis-

20 charged from, the turbine may be conducted in the pressure space 15. But in order to make the centrifugal pump self-starting the discharged water is conducted in the illus-

25 trated machine through an annular channel 16 into the suction space 17 of the centrifu-

gal pump. By this means it is made to fill this suction chamber and thus soon enables the pump to commence drawing water from below.

To increase the suctional effect of the

30 water discharged from the turbine 11 into the suction pipe 17 of the pump the direction of the discharging mouth 18 of the channel 16 is made such that the water issuing from the said mouth 18 and passing into the pump

35 blades or channels flows in the same direction as the water current sucked in by the pump. The suctional effect of the water discharged from the turbine then supplements the sucking action of the pump.

40 To render it unnecessary to look after the machine unit the water discharged from the turbine 11 is used for lubricating the bearings 19 of the shaft 10. The water employed for this purpose may be conducted to the

45 bearings through a passage or passages 20. By this arrangement the pump can run without hazard in air until the suction pipe 17 is filled with water and the pump commences delivering. As the water used for driving

50 the turbine is generally clean, it may be employed for preventing the channels 21 of the pump from becoming clogged in cases in which the water to be pumped is muddy. To this end the clean water discharged from the

55 turbine may be conducted straight into the blades or channels 21 of the pump.

In order to enable the pump to yield a large output with a small head and yet to run at a high speed, the blades 21 of the

60 pump rotor 22 are preferably made screw or spiral shaped as indicated in Fig. 2. By using a single-stage turbine 11 directly coupled with the pump rotor 22 the machine casing 23 may be constructed in such a man-

65 ner that when the cover 24 is removed the

whole revolving part, i. e. the shaft 10 together with the turbine rotor 11 and the pump rotor 22, may be lifted out in its entirety.

As will be seen from Fig. 1, this convenient removal of the rotating part of the machine is possible even in the case of a pump rotor 22 whose outside diameter is greater than that of the turbine 11. In such cases the admission channel 13 for introducing impelling water under a high pressure and the guide members 14 of the turbine, and all other parts of the casing whose diameters are smaller than that of the pump rotor 22, are arranged in the cover 24.

The axial thrust which, particularly in high-speed pumps, is often very considerable, is counteracted in accordance with the invention by an automatic balancing contrivance which, instead of being fed in the ordinary way with water under pressure taken from the gap between the rotor and stator of the pump, is fed with water under high pressure from the conduit leading into the turbine. The axial thrust counterbalancing device itself may be made in different ways. Two types of this device are employed in the machine illustrated, although one type will often be sufficient.

Impelling water at a high pressure is led 25 from the admission chamber 13 of the turbine 11 through a channel 25 situated within (or if need be without) the machine casing 23 and caused to impinge upon or press against the lower surface of the peripheral 100 portion 26 of the pump rotor. The water under pressure, on its way to the counterbalancing chamber 28 in which it operates to lift the rotor, is preferably made to pass through an exchangeable nozzle 27 by which 105 the quantity of water required for obtaining the counterbalancing or lifting effect may be regulated at will. The peripheral ring 26 is adapted to form two gaps at 29 between the rotor and the casing 23. The more these 110 gaps 29 are widened the more water will flow out from the counterbalancing chamber 28 into the pressure space 15 and the suction space 17 of the pump and the axial thrust from above to below will then predominate, 115 whereby the size of the regulating gaps 29 will be decreased. Finally a pressure will be produced in the counterbalancing chamber 28 by which the effect of the axial thrust of the rotor is counterbalanced.

The effect of the counterbalancing device that acts upon the underside of the pump rotor may be supplemented by another thrust balancing device which acts upon the surfaces of the turbine rotor, particularly the lower surface 30 of this rotor. To this end the impelling water under high pressure is made to flow through a passage 31 into the narrow counterbalancing chamber 32 which is closed more or less by cylindrical joint 33

and a variable gap 34 that acts like the gaps 29. In addition to this counterbalancing arrangement, operated by impelling water under high pressure, another axial thrust 5 counterbalancing device may be arranged in accordance with the invention at the upper surface 35 of the turbine rotor 11 and this latter device may be supplied with a part of the impelling water from the admission gap 10 between the turbine rotor blades and the stationary rotor guide blades. In the illustrated constructional form of the invention the water from the said admission gap flows through the cylindrical joint 36 into the upper 15 counterbalancing chamber 37 and after exerting pressure upon the pressure surface 35 it passes through the variable gap 38, whose throttling effect changes as the shaft is shifted, and through the short passage 39 into the annular passage 16 that leads into the suction space of the pump. In cases in which the thrust balancing device comprises both a lower thrust balancing device acting on the lower surface 31 of the turbine rotor 20 and operated by the water under pressure taken from the admission chamber 13, and an upper thrust balancing device acting on the upper surface 35 of the turbine rotor and operated by water taken from the admission gap, the variable throttle passage 34 in the former device may be dispensed with so that there will be only one variable throttle passage 38.

The axial thrust equalizing arrangement 35 at the turbine rotor 11 is particularly advantageous in cases in which, contrary to the arrangement shown in the drawing the pump rotor 22 is of smaller diameter than the turbine rotor 11. 40 If the three illustrated axial thrust balancing devices are all used together it will be found preferable to arrange a part of the balancing device that acts on the lower side of the rotor 11 in an intermediate piece 40 because this will make it easier to take the machine to pieces.

It will now be obvious that by the novel and peculiar combination of a propelling turbine with a centrifugal pump illustrated and 50 described herein a comparatively small, light machine unit is obtained in which all the active forces are mutually counterbalanced. Therefore there is no necessity for fixing the machine on a floor or seat and a very light 55 portable machine unit results.

In order to still further enhance the removability of the pump the upper connecting necks 41 and 42 are preferably arranged as shown in Fig. 3 in such a way that their 60 flanges or hose connection members do not project beyond the parts of greatest diameter of the casing, as for example the flanges 43 in the constructional form of machine illustrated in the accompanying drawing.

65 In order to keep the connecting neck 41 with-

in the imaginary cylinder surrounding the flanges 43 of the casing it may be necessary to arrange this neck 41 in an oblique position as shown in Fig. 3. To enable the machine unit to be easily rolled along on the 70 floor the two flanges 43 are made equal in diameter.

To further simplify the taking apart of the machine unit the rotor of the turbine is 75 preferably joined to the pump rotor by means of a screw thread 44, Fig. 1, which tends to screw in tighter when the propelling force of the turbine is applied. A connection of this kind necessitates no special securing or 80 fixing means, because the direction of rotation of the turbine can never be reversed. By this manner of joining the rotors the keys which are ordinarily used to transfer the torque of the turbine to the main shaft 85 of the machine, and then again from this shaft to the rotor of the driven machine, may be dispensed with. In some cases the shaft connecting the two rotors may be entirely done away with and the rotors may be arranged to rotate on short pivots protruding 90 from their upper and lower ends.

The thread 44 should have ample play and the centering of the two rotors 11 and 22 may be accomplished by means of the cylindrical parts 45, 46.

95 I claim:

1. A machine unit comprising, a casing containing a single-stage high-pressure water-impelled turbine with its bladed rotor directly coupled to a rotary pump having a 100 rotor with spiral water-impelling channels, whereby large quantities of water can be raised to any low height without throttle devices in spite of a high speed of revolution of the said rotors, and means for balancing 105 the thrust of the rotor comprising passages whereby the impelling water of the turbine automatically acts upon the pump rotor at the part where its diameter is greatest.

2. A machine unit comprising, a casing containing a single-stage high-pressure water-impelled turbine with its bladed rotor directly coupled to a rotary pump having a 110 rotor with spiral water-impelling channels, whereby large quantities of water can be raised to any low height without throttle devices in spite of a high speed of revolution 115 of the said rotors, and a thrust balancing arrangement comprising a primary thrust-balancing device adapted to be operated by impelling water taken from the point of its admission into the turbine, and a secondary thrust-balancing arrangement adapted to be operated by water taken from the gap between the turbine rotor and its stator.

3. A machine unit comprising, a casing containing a single-stage high-pressure turbine with its rotor directly coupled to a rotary pump having a rotor with spiral water-impelling channels, whereby 120 large

quantities of water can be raised to any low height without throttle devices in spite of a high speed of revolution of the said rotors, a suction conduit associated with the pump, and passages for conducting the impelling water discharged from the turbine into the suction conduit.

4. A machine unit comprising, a casing containing a single-stage high-pressure water-impelled turbine with its rotor directly coupled to a rotary pump having a rotor with spiral water-impelling channels, whereby large quantities of water can be raised to any low height without throttle devices in spite of a high speed of revolution of the said rotors, and means for balancing the thrust of the rotor comprising passages whereby the impelling water of the turbine automatically acts upon the pump rotor at the part where its diameter is greatest, a suction conduit associated with the pump, and passages for conducting the impelling water discharged from the turbine into the suction conduit.

5. A machine unit comprising, a casing containing a single-stage high-pressure turbine with its rotor directly coupled to a rotary pump having a rotor with spiral water-impelling channels, whereby large quantities of water can be raised to any low height without throttle devices in spite of a high speed of revolution of the said rotors, rotor bearings in the said casing, and passages for conducting the impelling water discharged from the turbine into the said bearings.

6. A machine unit comprising, a casing containing a single-stage high-pressure water-impelled turbine with its rotor directly coupled to a rotary pump having a rotor with spiral water-impelling channels, whereby large quantities of water can be raised to any low height without throttle devices in spite of a high speed of revolution of the said rotors, and means for balancing the thrust of the rotor comprising passages whereby the impelling water of the turbine automatically acts upon the pump rotor at the part where its diameter is greatest, rotor bearings in the said casing, and passages for conducting the impelling water discharged from the turbine into the said bearings.

7. A machine unit comprising, a casing containing a single-stage high-pressure turbine with its rotor directly coupled to a rotary pump having a rotor with spiral water-impelling channels, whereby large quantities of water can be raised to any low height without throttle devices in spite of a high speed of revolution of the said rotors, and a passage for conducting impelling water discharged from the turbine into the said spiral water-impelling channels of the pump.

8. A machine unit comprising, a casing

containing a single-stage high-pressure water-impelled turbine with its rotor directly coupled to a rotary pump having a rotor with spiral water-impelling channels, whereby large quantities of water can be raised to any low height without throttle devices in spite of a high speed of revolution of the said rotors, and means for balancing the thrust of the rotor comprising passages whereby the impelling water of the turbine automatically acts upon the pump rotor at the part where its diameter is greatest, and a passage for conducting impelling water discharged from the turbine into the said spiral water-impelling channels of the pump.

9. A machine unit comprising, a casing containing a single-stage high-pressure turbine with its rotor directly coupled to a rotary pump having a rotor with spiral water-impelling channels, whereby large quantities of water can be raised to any low height without throttle devices in spite of a high speed of revolution of the said rotors, and a passage for conducting impelling water discharged from the turbine into the said spiral water-impelling channels of the pump, the mouth of the said passage being adapted to lead out the said discharged water in the direction of flow of the main current of water impelled by the pump, whereby its sucking effect is increased.

10. A machine unit comprising, a casing containing a single-stage high pressure water-impelled turbine with its rotor directly coupled to a rotary pump having a rotor with spiral water-impelling channels, whereby large quantities of water can be raised to any low height without throttle devices in spite of a high speed of revolution of the said rotors, and means for balancing the thrust of the rotor comprising passages whereby the impelling water of the turbine automatically acts upon the pump rotor at the part where its diameter is greatest, and a passage for conducting impelling water discharged from the turbine into the said spiral water-impelling channels of the pump, the mouth of the said passage being adapted to lead out the said discharged water in the direction of flow of the main current of water impelled by the pump, whereby its sucking effect is increased.

11. A machine unit comprising, a casing containing a high-pressure water-impelled turbine with its bladed rotor directly coupled to a rotary pump adapted for a high speed of revolution, and means for balancing the thrust of the rotor comprising passages whereby the impelling water of the turbine automatically acts upon the pump rotor at the part where its diameter is greatest.

12. A machine unit comprising, a casing containing a high-pressure water-impelled

- turbine with its bladed rotor directly coupled to a rotory pump having a rotor adapted for a high speed of revolution, and a thrust balancing arrangement comprising a primary thrust-balancing device adapted to be operated by impelling water taken from the point of its admission into the turbine, and a secondary thrust-balancing arrangement adapted to be operated by water taken from the gap between the turbine rotor and its stator. 10
13. A machine unit comprising, a casing containing a high-pressure water-impelled turbine with its rotor directly coupled to a rotary pump having a rotor adapted for a high speed of revolution, and means for balancing the thrust of the rotor comprising passages whereby the impelling water of the turbine automatically acts upon the pump 15 rotor at the part where its diameter is greatest, a suction conduit associated with the pump, and passages for conducting the impelling water discharged from the turbine into the suction conduit. 20
14. A machine unit comprising, a casing containing a high-pressure turbine with its rotor directly coupled to a rotary pump having a rotor adapted for a high speed of revolution, rotor bearings in the said casing, and passages for conducting the impelling water discharged from the turbine into the said bearings. 25
15. A machine unit comprising, a casing containing a high-pressure turbine with its rotor directly coupled to a rotary pump having a rotor with spiral water-impelling channels, and a passage for conducting impelling water discharged from the turbine 30
- into the said spiral water-impelling channels of the pump. 40
16. A machine unit comprising, a casing containing a high-pressure turbine with its rotor directly coupled to a rotary pump having a rotor with spiral water-impelling channels, and a passage for conducting impelling water discharged from the turbine into the said spiral water-impelling channels of the pump, the mouth of the said passage being adapted to lead out the said discharged water in the direction of flow of the main current of water impelled by the pump, whereby its sucking effect is increased. 45
17. A machine unit comprising, a casing containing a high-pressure turbine with its rotor directly coupled to a rotary pump having a rotor with water-impelling channels, and a passage for conducting impelling water discharged from the turbine into the said water-impelling channels of the pump. 50
18. A machine unit comprising, a casing containing a high-pressure turbine with its rotor directly coupled to a rotary pump having a rotor with water-impelling channels, and a passage for conducting impelling water discharge from the turbine into the said water-impelling channels of the pump, the mouth of the said passage being adapted to lead out the said discharged water in the direction of flow of the main current of water impelled by the pump, whereby its sucking effect is increased. 55

In testimony whereof I have signed this specification.

FRANZ LAWACZECK.
